(57) **CLAIM**

The ornamental design for a closure, as shown and described.

DESCRIPTION

FIG. 1 is a front isometric view of a first embodiment of a closure showing our new design;

FIG. 2 is a top view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a front isometric view of a second embodiment of the closure showing our new design;

FIG. 8 is a top view of the second embodiment;

FIG. 9 is a front elevational view of the second embodiment;

FIG. 10 is a rear elevational view of the second embodiment;

FIG. 11 is left side elevational view of the second embodiment;

FIG. 12 is a right side elevational view of the second embodiment;

FIG. 13 is a front isometric view of a third embodiment of a closure showing our new design;

FIG. 14 is a top view of the third embodiment.

FIG. 15 is a front elevational view of the third embodiment;

FIG. 16 is a rear elevational view of the third embodiment;

FIG. 17 is left side elevational view of the third embodiment; and,

FIG. 18 is a right side elevational view of the third embodiment.

The broken lines represent unclaimed subject matter.
